UNITED STATES PATENT OFFICE.

CHARLES C. LEWIS, OF BURLINGTON, NEW JERSEY.

RAILROAD-TIE.

1,146,721.

Specification of Letters Patent. Patented July 13, 1915.

Application filed May 20, 1915. Serial No. 29,306.

To all whom it may concern:

Be it known that I, CHARLES C. LEWIS, a citizen of the United States, and a resident of Burlington, in the county of Burlington and State of New Jersey, have invented a new and Improved Railroad-Tie, of which the following is a full, clear, and exact description.

My invention relates to railroad ties, and 10 has reference more particularly to a tie comprising a casing filled with ballast.

An object of the invention is to provide a simple, strong and inexpensive railroad tie which has detachable rail attaching means 15 whereby rails can be easily and quickly replaced, and which attaching means will prevent lateral displacement of the rails on the tie.

A further object of the invention is to 20 provide removable reinforcing members adapted to coöperate with the rail securing means whereby the rail is positively locked to the tie.

With the above and other objects in view, 25 the nature of which will more fully appear as the description proceeds, the invention consists in the novel construction, combination and arrangement of parts as herein fully described, illustrated and claimed.

30 In the accompanying drawings, forming part of the application, similar characters of reference indicate corresponding parts in all the views.

Figure 1 is a plan view of a railway tie 35 embodying my invention; Fig. 2 is a longitudinal section on line 2—2, Fig. 1; Fig. 3 is a cross section on line 3—3, Fig. 2; and Fig. 4 is a fragmentary bottom view of the tie with the bottom plate removed.

40 Referring to the drawings, 5 represents an elongated hollow casing tapering slightly toward the bottom to facilitate the filling of the casing with ballast. The bottom of the casing is open and fits into a bordered 45 base plate 6, which borders prevent the casing 5 from moving on the base plate. Secured to the top of the casing adjacent each end is a rail bed 7, one of the beds having an integral flange 8 adapted to engage one 50 side of the base of the rail. An under-cut 55 groove 9 is provided at the other end of the rail bed central with the flange 8. Fitting snugly into said under-cut groove is a rail clamp 10. The other rail bed 7 has two alining under-cut grooves 9 each engaged by a corresponding rail clamp 10. The

clamps 10 are maintained against the rail by spikes 11 which pass through openings 12 purposely provided in the top of the casing 5. The stem of each spike is forked to engage a rib 13 which will open the stem of the spikes and lock the same in the casing. Each rib 13 forms a part of a detachable 60 filler 14 which reinforces the casing under the rails. The reinforcing filler comprises 65 a wall 15 adapted to extend transversely of the casing and having side-wall extensions 16 inclined or beveled the same as the sides of the casing 5, so as to snugly fit thereto. The depth or height of the reinforcing member 70 14 is that of the depth of the casing 5, so that the reinforcing member also rests on the base plate 6. The rib 13 projects from the wall 15 of the reinforcing member 75 and is thicker at the bottom than at the top, as best shown in Fig. 3.

The tie is formed as follows: The casing 5 is placed with its open bottom up. Each reinforcing member 14 is placed at a corresponding opening 12; the ballast is poured 80 into the casing; the base plate 6 is then placed over the casing and secured thereto by any suitable means. The tie so formed is ready to receive rails on its rail beds 7. The rails can then be engaged by the corresponding 85 rail clamps 10 which are then locked to the tie by means of the spikes 11. The ballast may be concrete, sand or any other similar material.

I claim:

1. In a railway tie, a casing open at the bottom, a base plate engaging the open end of the casing, said plate having borders preventing the casing from moving on the plate, rail beds on the top of said casing, reinforcing members within said casing under said beds, rail clamps associated with said beds, and spikes for locking said clamps to the beds, said spikes having means adapted to engage the reinforcing members whereby 95 the spikes are locked to the casing.

2. In a railway tie, a downwardly tapered casing open at the bottom, a bordered base plate engaging the open end to prevent the casing from moving on the plate, rail beds 105 associated with the top of the casing, said beds having under-cut grooves, rail clamps fitting into the under-cut grooves, removable reinforcing members within said casing under said bed plates, and spikes for locking 110 said clamps to the bed, said spikes having a forked stem, said reinforcing member hav-

ing a rib adapted to engage the forked stem of a spike whereby the stem is spread within the casing when forced thereinto.

3. In a railway tie, a downwardly tapered casing open at the bottom, rail beds secured to the top of said casing, reinforcing members fitting snugly into said casing transversely thereof, each of said bed plates having dovetailed slots, rail clamps fitting into said slots, said casing having openings adjacent the bed plates in alignment with the dovetailed slots, spikes having forked stems adapted to fit in said openings and whereby the clamps are locked to the bed, each of the reinforcing members having a rib adapted to be engaged by the forked stem to spread the same within the casing, and a bordered base plate adapted to engage the open end of the casing so that the borders of the plate prevent the movement of the casing on the plate.

4. In a railway tie, a downwardly tapering casing open at the bottom, a base plate engaging the open end, including means

preventing the casing from moving on the plate, rail beds on the top of the casing, rail clamps detachably associated with said bed plate, spikes adapted to fit into the top of the casing and engaging the clamping members whereby the clamping members are locked to the beds, reinforcing members fitting detachably into the casing, each comprising a wall having lateral extensions fitting snugly against the side of the casing with said wall extending transversely of the casing, and a rib extending from said wall, each spike having a bifurcated stem adapted to engage the corresponding rib of a reinforcing member to lock the spikes to the casing.

In testimony whereof I have signed my name to this specification in the presence of two subscribing witnesses,

CHARLES C. LEWIS.
